United States Patent Office

Des. 200,985
Patented Apr. 27, 1965

200,985

FONT OF TYPE

Richard K. Gerlach, Gardena, Calif., assignor to The National Cash Register Company, Dayton, Ohio, a corporation of Maryland

Filed June 29, 1964, Ser. No. 80,609

Term of patent 14 years

(Cl. D64—12)

The figure on the drawing is a face view of a font of type showing my new design.

The dominant features of the design reside in the portions shown in full lines.

This application is a continuation-in-part of my pending application Serial No. D72,562, filed November 20, 1962, and now abandoned.

I claim:

The ornamental design for a font of type, substantially as shown and described.
